UNITED STATES PATENT OFFICE.

OSCAR L. BARTLETT, OF MOUND CITY, ILLINOIS.

HAMPER.

1,190,847.

Specification of Letters Patent. Patented July 11, 1916.

Application filed March 29, 1915. Serial No. 17,761.

To all whom it may concern:

Be it known that I, OSCAR L. BARTLETT, a citizen of the United States, residing at Mound City, in the county of Pulaski and 5 State of Illinois, have invented a new and useful Improvement in Hampers, of which the following is a specification.

This invention may be termed a "trunk" or lidless hamper, consisting of two separate hampers without the usual cover, the tops of the hampers interlocking for carriage purposes, both hampers being filled through the bottom of the upper one, and sealed by replacing the bottom, the bottoms 15 of the two hampers when joined for shipment practically forming end members.

In manufacturing hampers of the usual type the wooden lid for the larger end usually makes up one fourth of the total 20 cost of the hamper, and with my device this cost is entirely avoided, and I also save in handling and packing as two hampers are filled and handled at the same time.

In the accompanying drawings: Figure 1 25 is a side elevation of the two hampers united. Fig. 2 is a detail vertical section, showing the manner in which the hampers interlock. Fig. 3 is an end view.

In these drawings I have shown the two 30 hampers constructed of the usual staves 1 and hoops 2, the hampers having a greater diameter at one end than at the other. One of these hampers has adjacent its larger end a hoop 3 the staves projecting beyond 35 the hoop, the outer faces of the projecting portions of the staves being beveled. The other coöperating hamper has a hoop 4 which projects beyond the ends of the staves, the inner face of the projecting portion 40 of the said hoop being beveled, so that when the larger ends of the hampers are brought together, the ends of the staves

of one hamper engage those of the other, the beveled staves of one hamper engaging the beveled face of the hoop 4, and the two 45 hoops also engaging. Headed pins 5 are fixed in the hoops 3 and 4 and wires 6 wrapped about said pins lock the two hampers together.

The smaller ends of the hampers are fitted 50 with bottom or end members 7 held in place by metal strips 8 nailed to the members 7 and to the smaller hoops 2. These end members are perforated for passage of a bolt 10, the perforations 9 being in the center of the end members, and the bolt, which 55 passes longitudinally through both hampers, is locked by a nut 11.

While both locking means are provided the bolt is required only with heavy articles 60 such as potatoes and onions. When the bolt is employed the wire 6 may be used or omitted as desired. With light articles, such as lettuce the bolt may be omitted and the wire 6, or its equivalent, only used. 65 It is of course understood that the upper end member 7 is secured in place after the two hampers are filled through said end.

What I claim is:

A packaging device comprising two 70 hampers, each hamper having staves and exterior hoops, the staves of one hamper projecting beyond the hoop and having the outer faces of their projecting portions 75 beveled, the hoop of the coöperating hamper projecting beyond the staves and having its inner projecting face beveled to engage the beveled portions of the staves of the other hamper.

OSCAR L. BARTLETT.
